SPRING HINGE

Emil Bommer, Brooklyn, N. Y.; Gustav Bommer,
John F. Voelkel, and Charles F. Gehrmann,
executors of said Emil Bommer, deceased

Application December 26, 1934, Serial No. 759,171

2 Claims. (Cl. 16—189)

This invention relates to spring hinges for doors and the invention has for its object and purpose to provide improved means whereby at will to adjust the door-closing torsion spring to the needful requirements, or to the desired requirements, of the particular door with which the spring is, or is to be, associated.

An object of the invention is to so mount the torsion spring and to provide therefor such simple and adjusting mechanism that the spring by means of a screw driver or similar tool, may be given that fine degree of tensional force or stored power which best effects a closing of the door in keeping with a person's desire or fancy.

Another object of the invention is to so arrange and connect a cylindrically coiled spring that one end or portion thereof will with the turning of the door spindle itself be turned or twisted about the longitudinal axis of the spring.

Another object of the invention is the provision of a spring hinge arrangement which is especially useful and efficient in connection with door check and closer devices of the type illustrated in my co-pending application filed December 26, 1934, Serial No. 759,170, but I desire to make it understood that the present invention involves principles of general application, useful in a wide variety of hinges in which a spindle or a pintle turns in accompaniment with the opening and closing movements of the door.

Still another object of the invention is to provide a construction in which, where an enclosing casing is used for the working parts, the adjustment of the torsion spring may be accomplished from the outside of the casing.

With the foregoing and other objects in view, the invention consists in the novel construction, combination and arrangement of parts as hereinafter more specifically described with reference to the example illustrated in the accompanying drawing, wherein like characters of reference denote corresponding parts throughout the several views, and in which:

Figure 1 represents a vertical sectional view through a door check and closer embodying a spring hinge construction made in accordance with my invention, this view being taken on the line 1—1 of Fig. 2;

Fig. 2 is a cross sectional view, taken on the line 2—2 of Fig. 1 and showing the worm gear arrangement by which the fine adjustment is effected and maintained.

Fig. 3 is a side elevation of the upper retaining collar or ring to which the spring is attached; and

Fig. 4 is a similar view of the worm collar or ring to which the spring is attached.

Referring now to the drawing in which for purposes of illustration I have shown an example of my invention as embodied in a door check and closer, 5 denotes a casing of appreciable length and generally of cylindrical form, having oppositely disposed leaves 6 adapted to embrace a stile 7 or other suitable supporting part or frame adjacent the door, and 8 denotes the hinge spindle or pintle which is shown in the present instance as provided with a four-sided portion 9 adapted to engage a correspondingly formed socket 10 in the door whereby, as is well known in the art, to connect the spindle and door so that these two parts will turn together.

The casing 5 is represented as being provided with an integral bottom portion 11 above which the interior of the casing is cylindrical in form, and in the present embodiment the top of the casing comprises a cap closure 12 having peripheral screw-threads whereby to be screw-threaded at 13 into the upper end of the body of the casing. The spindle 8 within the interior of the casing is provided with a motion transmission connector 14 of cylindrical form and which has telescoping fit on a valve member 15. For turning the valve 15 with the turning movement of the spindle while permitting the valve to be moved upwardly as the door is opened and to be moved downwardly against checking fluid medium as the door is closed, a sliding key connection is provided between the connector 14 and the valve 15 and comprises the provision in the cylindrical wall of the connector of elongated slots or guideways 16 which are parallel with the longitudinal axis of the valve and in these guideways are slidably fitted suitable keys 17 provided for the purpose on the valve. The motion-transmitting connector and the valve do not of themselves constitute a part of the present invention and therefore they need not be further described herein, but it is in place to state here that these parts are fully illustrated, described and claimed in my co-pending application above identified.

18 denotes a seating or retaining collar for the lower end of the cylindrically coiled torsion spring 19, and with this collar there is combined a hobbed or worm wheel portion 20. This collar, as shown in Fig. 1, is of larger interior diameter than the exterior diameter of the valve 15 and of the motion transmission connector 14, so as to be passed downwardly around these parts to rest upon the bottom end 11 of the casing. With respect to the interior diameter of the casing just above the

bottom 11, the outside diameter of this collar is such that its outer face will contact with the inner face of the casing wall. Above an annular shoulder 21 the interior of the casing is slightly of larger 5 diameter in order suitably to provide room for the worm wheel portion 20 provided on this collar. The top portion of this collar is made in the form of a seat on which to retain the lower end of the torsion spring 19 and it will be seen that this seat 10 comprises an annular ledge or shoulder 22 adjacent an upwardly extending flange 23 which fits inside the coils of the spring. In the flange 23 is provided an open notch 24 in which is engaged the lower terminal 25 of the spring whereby to 15 anchor the lower end of the spring to the collar.

Manual means operative from the outside of the casing is provided whereby to adjust or turn the collar rotatably and thereby turn or twist the torsion spring about its longitudinal axis, and also 20 whereby to secure or retain the collar and hence the spring in adjusted position. This means consists in the provision of a worm stem or pin 26 disposed in a bore 27 of suitable size, which bore is so made that a portion thereof communicates 25 through an opening 28 with the interior of the casing to permit inter-engagement of a plurality of the teeth of the screw stem with a plurality of the teeth on the worm wheel 20. Preferably and as shown, the outer end of the bore 27 is enlarged 30 sufficiently to permit the entrance of a flange 29 provided on the stem for the purpose of seating against a stop shoulder 30. Suitable packing 31 is inserted in the enlarged bore against the flange 29 and a sealing nut or gasket 32 is screw-threaded 35 into the enlarged bore against the packing whereby to prevent any leakage of the checking medium or fluid around the outer end of the stem while permitting the teeth of the stem and of the worm gear to be lubricated. The outer end of the 40 stem is provided with a notch 33 adapted to receive the end of a screw driver or similar tool whereby to provide for the manual turning of the worm stem and hence of the lower retaining collar in mesh therewith.

45 For the upper end of the torsion spring there is provided a seating or retaining collar 34 having an underneath annular shoulder or seat 35 and adjacent thereto a depending flange 36 which comes inside the coils of the spring, said flange 50 36 having an interior diameter greater than the exterior diameter of the motion-transmitting connector 14 so as to permit axial adjustment of the connector with the spindle 8 to which the connector is rigidly attached. The depending flange 55 36 is provided with an open notch 37 in which is engaged the upper terminal 38 of the spring whereby the spring is secured to the upper retaining collar so that these parts will be turned together. The upper retaining collar 34 is formed 60 with a central upstanding flange 39 having a circular exterior face and this flange as well as the collar itself having a polygonally shaped aperture 40, which, in the present instance, consists of four equal faces. For interlocking with the aperture 40, the spindle 8 is provided with a four-sided portion 41. Under this arrangement, when the portion 41 is engaged in its opening, the collar and spindle will turn in unison, and during assembly the spindle may be applied to the collar 65 70 when the latter has been turned into that position in which the spring has been turned or twisted so as to give it a preliminary tension.

The cap 12 is formed exteriorly with a central enlargement or hub 42 having a bearing 43 for the 75 smooth portion 44 of the spindle; and this bearing

opening at the outer end of the portion 42 is enlarged to provide for the insertion of packing 45 and a nut 46 which is screw-threaded into the opening around the spindle. Adjacent and below the smooth portion 44 the spindle is provided with a disk 47 having turning fit in a suitable recess 48 provided for the purpose in the underface of the cap. Surrounding the flange 40 of the retaining collar 34 is a disk 49 of larger diameter than the disk 47 and which is adapted to be engaged by the top face of the retaining collar 34 and to rest upon an annular ledge or shoulder 50 provided in the casing wall adjacent and below the screw-threads 13. Suitable ball elements 51 are disposed between the disks 47 and 49 and in suitable raceways 52 provided in these cooperating ball bearing disks. Under this arrangement the spindle and as well the weight of the door, if the door is supported upon the spindle, are supported in the upper part of the casing upon the ledge 50, and when the cap is screwed down to its full extent its underneath portion 53 engages the upper face of the disk 49 so as to retain the latter firmly against the ledge 50 and hence in its seat between the casing and the cap. The torsion spring is of such length relative to the distance between the two retaining collars that when the cap is applied to the casing and screwed down tightly thereinto to the full extent permitted to it, the torsion spring will be considerably compressed 25 between the two collars against which it acts, and this compression taken in connection with the twist which may be given to the spring when the portion 41 is engaged with the opening in the collar, will give the spring at the time of assembly 30 an initial or preliminary tension.

In assembly, after inserting the lower retaining collar in place upon the bottom of the casing, the torsion spring is inserted and its lower terminal is engaged with the notch in the collar. The screw stem may then be applied so as to engage its teeth with the teeth of the worm gear, thereby locking this lower retaining collar against rotation except upon the proper manipulation of the worm stem from the exterior of the casing. The upper collar is then applied to the spring followed by the application of the disk 49 and the ball elements. Before the cap is applied or screwed in place, the spindle is applied, inserting the square portion thereof into the corresponding aperture 50 of the retaining collar in such manner that the spring is given the desired preliminary tension. After the spindle has been applied to the door, the worm stem may be manipulated so as to give the torsion spring the desired degree of stored power 55 which is thought to be best adapted to the requirements of the particular door with which the hinge is associated.

As many changes could be made in the above described construction and many apparently widely different embodiments of this invention could be made without departing from the scope thereof; it is intended that all matter contained in the above description or shown in the accompanying drawing shall be interpreted as illustrative and not in a limiting sense.

I claim:

1. In a hinge of the class described, the combination of a door supporting spindle, a jamb fixture in the form of a vertical casing having a closed bottom and an open screw-threaded upper end, a seat formed in the interior casing wall contiguous said upper end, a door closing spring connection in the casing having means for engaging the spindle, a screw-threaded cap closure for en-

gaging the screw-threaded upper end of the casing, having therethrough a central journal opening receiving the spindle for rotation and a supporting bearing for the spindle receivable in said 5 seat for rotatably supporting the spindle therein, said closure, when applied, adapted to force compression of the spring in the casing below the seat and to entirely enclose the bearing and confine the same in its seat against upward displacement.

10 2. In a hinge of the class described, a casing adapted to be fixed to the jamb and having an internal seat contiguous its upper end, a spindle adapted to support the door and turn therewith, a spring in the casing coacting between the 15 spindle and casing to cause winding of the spring

upon rotation of the spindle on the opening movement of the door, a bearing for rotatably supporting the spindle upon said seat including a mounting member which encircles the spindle above the spring, confining the latter, having support upon the seat and a circular member fixed to the spindle, with ball elements between said members, and a cap closure for the casing in which the spindle is journaled for rotation, having screw-threaded coaction with the casing above said 10 mounting member, said closure adapted to entirely encase the bearing and confine the same in its seat against upward displacement. 5
